UNITED STATES PATENT OFFICE.

ARCHER A. LANDON, OF BUFFALO, NEW YORK, ASSIGNOR TO AMERICAN RADIATOR COMPANY, OF CHICAGO, ILLINOIS, A CORPORATION OF NEW JERSEY.

AUTOMATIC DAMPER CONTROL.

1,256,143.

Specification of Letters Patent. Patented Feb. 12, 1918.

Application filed November 29, 1915. Serial No. 64,061.

To all whom it may concern:

Be it known that I, ARCHER A. LANDON, a citizen of the United States, residing at Buffalo, Erie county, in the State of New York, have invented certain new and useful Improvements in Automatic Damper Controls, of which the following is a full, clear, and exact specification.

My invention relates to improvements in heating apparatus, and the same has for its object more particularly to provide a reliable and efficient device for regulating the rate of consumption in a boiler.

One of the objects of the invention is to provide a damper which is movable bodily from the air inlet opening with which it contacts so that the entire area of the opening will be effective for the admission of air upon the slightest movement of the damper. Another object is to so mount the damper that when in its open position it will offer a minimum obstruction to the flow of gases from the boiler to the smoke pipe.

A further object is to so arrange and connect the upper and lower dampers of a boiler relatively to the flow of the inflowing currents of air that they will at all times be in a state of stable equilibrium whereby fluctuation or fluttering of the dampers is avoided.

Other objects of the invention will be referred to in the specification, and pointed out in the claims.

To the attainment of the aforesaid objects and ends my invention consists in the novel details of construction, and in the combination, connection and arrangement of parts hereinafter more fully described and then pointed out in the claims.

In the accompanying drawings showing an illustrative embodiment of the invention—

Figure 1 is a view in side elevation of a heating boiler equipped with the improved regulator.

Fig. 2 is a plan or top view thereof, and

Fig. 3 is a sectional view of the smoke hood on the line 3—3 of Fig. 2.

Referring to the drawings, 4 represents a heating boiler of any suitable type comprising a base 5 and a smoke hood 6 having an outlet 7 to which the smoke pipe is connected in the usual manner. The base 5 is provided with an air inlet opening 8, the flow of air therethrough being controlled by a pivotally mounted cover 9 which serves as a

damper, and which is arranged to open in a direction opposite to that of the inflowing current of air. The cover 9 is connected to the lower end of a transmission rod 10, the upper end of which is connected to one end 60 of an operating lever 11 pivotally supported intermediate its ends upon the boiler. This lever, which carries an adjustable weight 12, is automatically actuated to open and close the cover 9 in accordance with variations of temperature or pressure by any suitable mechanism. As shown the lever 11 is actuated by the expandable and collapsible vessel 13 of a thermosensitive controlling device actuated by the boiler. As the temperature increases the vessel 13 expands thus causing the lever 11 to rock about its pivot in a direction such that the end thereof to which the rod 10 is attached will be lowered thereby permitting the cover 9 to close, 75 whereas if the temperature decreases, the vessel 13 will contract, and the lever will be rocked in the opposite direction to open the cover 9.

The smoke hood 6 is provided with an air 80 inlet opening 14 within which is secured a frame 15 having inwardly extending flanges which form a seat 16 for a damper 17 when in its closed position. The damper 17 is carried by one end of a curved arm 18 which 85 passes through the opening 14, and has its other end secured to a rock shaft 19 rotatably supported upon the smoke hood and provided with a laterally extending arm 20 which is connected to the lever 11 by a link 21. 90

As the rock shaft 19 is rotated to move the damper 17 from its closed to its open position the damper will be moved bodily from its seat 16 thus effecting a rapid opening of the air inlet 14. Furthermore, by reason 95 of this bodily movement of the damper from its seat, the air inlet 14 will be opened throughout its entire area thus permitting a greater and more widely distributed flow of air through the inlet than is obtained with 100 the usual type of damper which is pivotally mounted, but not bodily movable. Another advantage which arises from so mounting the damper that it may be moved bodily from its seat is that when it is opened it will 105 lie substantially parallel to the direction of the flow of gases from the boiler to the smoke pipe, whereby the edge is presented to the flow of the gases thereby offering practically no obstruction to the passage of the gases. 110

This advantage is increased by inclining the portion 22 of the smoke hood 6 in which the inlet opening 14 is formed so that the plane of the damper seat 16 will be at an angle 5 with the axis of the smoke outlet 7. The inclined position of the inlet 14 will also serve to cause the inflowing current of air to enter in a direction parallel to the flow of the gases from the boiler to the smoke pipe 10 thereby avoiding any cross currents which tend to obstruct the free flow of such gases.

The parts are so adjusted and arranged that, when the lever 11 is moved to close the cover 9, the damper 17 will be opened, and 15 vice versa. As the damper 17 opens in the direction of the flow of the air through the opening 14 and the damper 9 opens in a direction opposite to that of the current of air flowing in at the opening 8 in the base of the 20 boiler, there will be at all times a balancing of the dampers, which will prevent any fluctuation or fluttering thereof, as a result of which an exact and even regulation of the draft through the boiler is obtained.

25 Having thus described my said invention, what I claim and desire to secure by Letters Patent is:—

1. The combination with a boiler having a smoke hood provided with an air inlet and 30 a smoke outlet, the plane of the air inlet being at an angle with respect to the axis of the smoke outlet and diverging from said axis in the direction of said smoke outlet whereby to cause the inflowing air to enter 35 the inlet in the direction of the flow of gases through the smoke outlet, of a damper within said smoke hood mounted to open in the direction of the inflowing air to control the flow of air through the inlet, and means 40 for opening and closing the damper, substantially as specified.

2. The combination with a boiler having a smoke hood provided with an air inlet and 45 a smoke outlet, the plane of the air inlet being at an angle with respect to the axis of the smoke outlet and diverging from said axis in the direction of said smoke outlet to cause the inflowing air to enter the inlet in the direction of the flow of gases through 50 the smoke outlet, of a damper within said smoke hood mounted to open in the direction of the inflowing air to control the flow of air through the inlet, said damper in its open position being substantially parallel to 55 the direction of the flow of gases from the boiler, and means for opening and closing the damper, substantially as specified.

3. The combination with a boiler provided

with a flue for conducting the gases therefrom, said flue having an air inlet, the plane 60 of the air inlet being at an angle with respect to the axis of the flue to cause the inflowing air to enter said inlet in the direction of the flow of gases through said flue, of a damper positioned within said flue and 65 movable bodily toward and away from said inlet to close and open the same whereby to control the flow of air therethrough, said damper in its open position being substantially parallel to the direction of the flow of 70 gases from the boiler, and means for opening and closing said damper, substantially as specified.

4. The combination with a boiler having a smoke hood provided with an air inlet and 75 a smoke outlet, the plane of the air inlet being at an angle with respect to the axis of the smoke outlet to cause the inflowing air to enter the inlet in the direction of the flow of gases through the smoke outlet, of 80 a damper positioned within the smoke hood and movable bodily toward and away from the air inlet to close and open the same whereby to control the flow of air therethrough, said damper in its open position 85 being substantially parallel to the direction of the flow of gases from the boiler, and means for opening and closing the damper, substantially as specified.

5. The combination with a boiler having a smoke hood provided with an air inlet and 90 a smoke outlet, the plane of the air inlet being at an angle with respect to the axis of the smoke outlet to cause the inflowing air to enter the inlet in the direction of the flow of gases through the smoke outlet, of 95 a damper positioned within the smoke hood and movable bodily toward and away from the air inlet to close and open the same whereby to control the flow of air therethrough, said damper in its open position 100 being substantially parallel to the direction of the flow of gases from the boiler, an arm having one end pivotally mounted upon the smoke hood adjacent the air inlet and its other end secured to the damper, and means 105 to actuate the arm to open and close the damper, substantially as specified.

Signed at the city of Buffalo, Erie county, in the State of New York, this 28th day of 110 October, one thousand nine hundred and fifteen.

ARCHER A. LANDON.
